UNITED STATES PATENT OFFICE.

FRED L. SHELDON, OF TACOMA, WASHINGTON.

HOBBYHORSE.

Application filed January 2, 1925. Serial No. 95.

This invention relates to improvements in hobby horses and has for its principal object to provide a device of that character wherein the body is supported by eccentrically mounted rollers which operate, when the horse is in use, to cause it to travel forwardly.

Another object is to provide a hobby horse of the character above stated wherein provision is made whereby certain of the rollers may be held disengaged from the floor to cause the horse to turn.

Other objects reside in the various details of construction and manner in which the supporting rollers are mounted.

In accomplishing these and other objects of the invention, I have provided the improved details of construction, the preferred forms of which are illustrated in the accompanying drawings, wherein—

Figure 1 is a perspective view of a hobby horse constructed in accordance with the present invention.

Figure 2 is a plan view of the same.

Figure 3 is a side elevation of the horse.

Figure 4 is a transverse sectional view through the body portion taken on the line 4—4 in Figure 3.

Referring more in detail to the drawings—

1 designates a horizontally disposed body board, rounded, at its opposite ends and tapered toward the forward end, and which is supported by means of two longitudinally extending rockers 2 and 3 attached to its under side by any suitable means and on which the board may rock longitudinally.

At the forward end of board 1 is fixed a standard 4 representing a horse's neck and head and at the opposite sides of the head are rings 5 through which reins 6 are slidably extended.

Mounted on the rearward portion of the board is a seat 7 and at opposite side edges of the board are stirrups 8 for the feet of the rider.

Pivots secured to outside of the opposite rockers in paired relation and adapted for oscillating contact with the floor or surface on which the device is used, are rollers 9 eccentrically mounted by pivot pins 10. Formed in the rollers about the pivot pins as the center points are arcuate slots 11 through which pins 12 fixed in the rockers, are extended to limit the pivotal movement of the rollers.

When the device is in use, the user sits on the back portion of board 1 and by motion of the body causes the device to rock forward and back. When the device is rocked toward the rear, the forward rollers, being lifted clear of the floor, move rotatably on pins 10 until upper end of slot 11 contacts pin 12 and thus limits their movement so that the mounting pin 10 is at the upper side of the roller and just forward of a vertical line through the center, as is shown in Figure 3, then as the device is rocked forwardly the rollers are brought against the floor and operate, due to their eccentric mounting, to push the body forwardly. As the body is thus rocked forwardly, the rear rollers swing about their pivot pins until the pins are at the top and then on the following rearward rocking of the body they act also to push it forwardly. Thus by the continued rocking movement, the horse will be caused to move forwardly.

For the purpose of guiding the movement of the horse, the ends of the reins 6 are attached to the opposite, front rollers 9 and by pulling on one or the other of these reins, the roller to which it is attached will be held up from engagement with the floor while the one at the other side is free to operate. This will cause the horse to turn toward the side of the inoperative roller.

While I have shown the rollers as limited in their movement by the pins 12 and slots 11, it is readily apparent that various other ways and means could be provided for thus limiting their movement, such as by pins being driven into the rockers against which the edges of the rollers would contact.

It is further apparent and it is intended also that such devices be made in various sizes and in different designs.

Having thus described my invention, what I claim as new therein and desire to secure by Letters-Patent, is:

1. A device of the character described comprising a body board, rockers fixed to said board on which it may be rocked forwardly and rearwardly on a supporting surface, rollers eccentrically mounted on said rockers in paired relation toward the front and rear thereof, and having radially curved surfaces adapted for oscillating contact with the supporting surface, and means for limiting the rotative movement of the rollers.

2. A device of the character described comprising a body board, rockers fixed to

said board on which it may be rocked forwardly and rearwardly on a supporting surface, rollers eccentrically mounted on said rockers in paired relation toward the front and rear thereof, and adapted for oscillating contact with the supporting surface, and having arcuate slots formed therein about the pivot points and pins fixed in the rockers and extended into the slots to limit oscillatory movement of the rollers.

3. A device of the character described, comprising a body board, rockers fixed to said board on which it may be rocked forwardly and rearwardly on a supporting surface, rollers eccentrically mounted on said rockers in paired relation toward the front and rear thereof, and having radially curved surfaces adapted for oscillating contact with the supporting surface, and adapted normally to be held in floor engaging position due to their weight and eccentric mounting

means for limiting the rotative movement of the rollers, and means for selectively lifting certain of the rollers from contact with the supporting surface.

4. A device of the character described, comprising a body board, supporting rockers fixed to the board for forward and rearward rocking, eccentrically mounted rollers fixed in paired relation to the rockers toward the forward and rearward ends thereof and adapted for oscillating contact with the supporting surface and operable to advance the body forwardly incidental to rocking thereof and reins attached to the opposite forward rollers whereby either may be held from contact with the surface for the purpose set forth.

Signed at Tacoma, Pierce County, Washington, this 19th day of December, 1924.

FRED L. SHELDON.
